UNITED STATES PATENT OFFICE.

JOSEPH FORSHEIM, OF GREAT NECK, AND JOSEPH KONIGSBERG, OF NEW YORK, N. Y.,
ASSIGNORS TO LENA S. FORSHEIM, OF GREAT NECK, NEW YORK.

SEAL-LOCK.

1,201,816.

Specification of Letters Patent.

Patented Oct. 17, 1916.

Application filed April 27, 1915. Serial No. 24,256.

To all whom it may concern:

Be it known that we, JOSEPH FORSHEIM and JOSEPH KONIGSBERG, citizens of the United States, and residents, respectively, of 5 Great Neck, in the county of Nassau and State of New York, and of the borough of Manhattan, in the city and State of New York, have invented a new and useful Improvement in Seal-Locks, of which the following is a specification.

The object of this invention is to provide a detector which must be mutilated before it can be removed.

Another object is to provide a detector 15 which must be mutilated before access can be obtained to parts behind the detector.

The invention more particularly comprises a protective strip which is held in position by suitable positioning means, such as 20 a locked cover, the strip being so located that it must be punctured or otherwise mutilated before the positioning means can be released to permit the removal of the protective strip. The positioning means may form part of a 25 holder for the protective strip or it may hold the strip in position on any suitable support.

The detector may be used for protecting an open compartment, a drawer, the door of a closed or locked compartment, a lock, the 30 key-hole of a lock, or wherever applicable, where it is desired to indicate that access has been obtained or attempted past the detector. It is to be understood that the mutilation of the detector should be such that it 35 will be rendered inapplicable for further use.

A practical embodiment of the invention is shown and described herein.

Figure 1 is a front view of a box illustrating our invention, Fig. 2 is a section taken in the plane of the line A—A of Fig. 1, Fig. 3 is a section taken in the plane of the line B—B of Fig. 1, Fig. 4 is a section taken in the plane of the line C—C of Fig. 1, Fig. 45 5 is a detail section taken in the plane of the line D—D of Fig. 1, Fig. 6 is a view similar to Fig. 1, showing the cover released, and the protective strip removed, and Fig. 7 is a detail section taken in the plane of the line 50 E—E of Fig. 6.

The protective strip is denoted by 1, which strip may be of paper or other suitable material which can be readily punctured or otherwise mutilated.

In the embodiment of our invention 55 shown, the detector is shown as applied to a lock box of well known form, in which the body of the box is denoted by 2, its cover by 3, the lock by 4 and its key-hole by 5. A laminated holder 6 is permanently secured to 60 the front of the box around the key-hole 5, to which holder is hinged a cover 7 which acts in connection with the holder as a positioning means for the strip 1. This cover is provided with a hole 8 in front of the key-hole 5, through which hole the protective strip is disclosed. This cover 7 is provided with a hook 9 arranged to enter a slot 10 in the holder and be engaged by a spring-pressed locking catch 11. This locking catch 70 11 is provided with a lip 12 under manual control for releasing the cover 7. A spring 13 may be provided for throwing the cover 7 open when released from the holder.

The manually operated releasing device 75 is back of the protective strip 1 and is in alignment with a hole 14 in the cover 7, through which hole the protective strip is disclosed. The protective strip exposed through this hole 14 in the cover, must be 80 mutilated before the lip 12 of the cover releasing device can be operated to release the cover. If desired, the holder may be provided with one or more impaling pins 15 in alignment with holes 16 in the cover for still 85 further securing the protective strip in position. It will thus be seen that the protective strip must be punctured and thereby mutilated to permit the insertion of the key into the keyhole 5 and also that the strip must be 90 punctured and thereby mutilated to gain access to the cover releasing means, before the cover can be released to permit the strip to be removed from the positioning means.

It is intended that the mutilation of the 95 protective strip be sufficient to render the strip inoperative for further use and it is also intended that if so desired a characteristic mark shall be placed upon the protective strip where the said mark will be ex- 100

posed through the opening in the cover, this serving as an additional guard against the reuse of the protective strip.

It is evident that the embodiment herein disclosed is only one of many embodiments which might be provided within the scope of our invention; hence we do not wish to limit ourselves to the structure herein shown and described, but

10. What we claim is:—

1. A lock, a protective strip, positioning means therefor, and a separate releasing device for the positioning means operable independently of the lock, said strip covering and protecting both the lock and the releasing device and requiring mutilation for gaining access to either.

2. A lock, a protective strip, positioning means therefor including a cover, and a separate releasing device for the cover operable independently of the lock, said strip covering and protecting both the lock and the releasing device and requiring mutilation for gaining access to either.

25. 3. A lock, a protective strip, positioning means therefor including a holder and its cover, and a separate releasing device for the cover, said strip covering and protecting

both the lock and the releasing device and requiring mutilation for gaining access to either.

4. A lock, a protective strip, positioning means therefor including a cover and a separate releasing device for the cover operable independently of the lock, said strip covering and protecting both the lock and a releasing device and requiring mutilation for gaining access to either, and said cover having holes therethrough for exposing the protective strip both at the lock and at the releasing device.

5. A lock, a protective strip, positioning means therefor including a holder and its cover and a separate releasing device for the cover operable independently of the lock, said strip covering and protecting both the lock and the releasing device and requiring mutilation for gaining access to either, and said cover having holes therethrough for exposing the protective strip at the lock and at the releasing device.

In testimony, that we claim the foregoing as our invention, we have signed our names this twenty-sixth day of April, 1915.

JOSEPH FORSHEIM.

JOSEPH KONIGSBERG.
